CLAIM

The ornamental design for a pipette controller, as shown and described.

DESCRIPTION

FIG. 1 is a rear perspective view of a pipette controller having an extended neck portion;
FIG. 2 is a rear elevation view thereof;
FIG. 3 is a right-side elevation view thereof;
FIG. 4 is a front elevation view thereof;
FIG. 5 is a left-side elevation view thereof;
FIG. 6 is a bottom plan view thereof; and,

(Continued)

FIG. 7 is a top plan view thereof.
The broken lines in the drawings depict portions of the pipette controller that form no part of the claimed design.

1 Claim, 6 Drawing Sheets
